UNITED STATES PATENT OFFICE.

CHARLES BAULK, OF KIDDERMINSTER, ENGLAND, ASSIGNOR OF ONE-HALF TO JAMES HUMPHRIES AND SONS, LIMITED, OF KIDDERMINSTER, ENGLAND.

MEANS FOR LUBRICATING THE PILE-WIRES OF LOOMS.

SPECIFICATION forming part of Letters Patent No. 730,201, dated June 2, 1903.

Application filed October 6, 1902. Serial No. 126,146. (No model.)

To all whom it may concern:

Be it known that I, CHARLES BAULK, a subject of the King of Great Britain, residing at No. 1 Franchise street, Kidderminster, England, have invented certain new and useful Improvements in Means for Lubricating the Pile-Wires of Looms, of which the following is a specification.

My invention relates to the lubricating of the wires used in forming the loop or pile of carpets and the like made on Jacquard and other like looms; and my invention has for its object to facilitate and improve the lubrication of the said wires as they are pulled out of the loops or pile of the carpet preparatory to being again introduced between the yarn and warp for the purpose of forming other loops, a process well known in this class of carpet-loom.

In order that my invention may be the better understood, I remark that it is usual to lubricate the wires, before mentioned, by hand by the use of cylindrical or roller brushes containing oil—that is, liquid lubricant—which oil frequently causes the pile of the carpet to become greasy and with carpets having a light ground gives the top a more or less soiled and discolored appearance. Great waste of oil also results from this the ordinary method of lubricating the pile-wires.

The object of my invention is to effect a uniform and efficient lubrication of each pile-wire in such a way that the objections hereinbefore referred to in the use of the ordinary hand method of lubrication are obviated.

In carrying my invention into effect I employ a solid lubricant and automatically apply the same to the under sides or edges of the pile-wires, or preferably to both the under and upper sides or edges, in the ways hereinafter described, and illustrated in the accompanying drawings.

I will describe my invention in connection with means for lubricating both sides or edges of the pile-wires.

For the lubricating of the upper edges of the pile-wires I employ a hard wax—such, for example, as paraffin-wax or composite candle-wax; but for the lubricating of the under

edges or sides of the said pile-wires I prefer to employ a softer wax, such as is obtained by the mixing with paraffin-wax when in a melted state of sperm-oil in about the proportion of seven parts, by weight, of paraffin-wax to two parts, by weight, of sperm-oil. The solid lubricants described are made into the form of cylinders somewhat resembling in appearance ordinary wax candles.

Figure 1 of the accompanying drawings represents in front elevation a portion of one side of a Jacquard loom, showing the ordinary mechanism by which the pile-wires are drawn out of the carpet and also the new or improved means for lubricating the said wires constituting my invention; and Fig. 2 is a plan of the same. Fig. 3 represents, partly in elevation and partly in section, the lubricating appliance detached, drawn to a larger scale than Figs. 1 and 2. Fig. 4 is a sectional view at right angles to Fig. 3. Fig. 5 represents, partly in plan and partly in horizontal section, the mechanism by which the lower solid lubricant is rotated, as is hereinafter explained; and Fig. 6 represents in plan the mechanism by which the upper solid lubricant is rotated, as is also hereinafter explained. Fig. 7 is a cross-section on the line *x x*, Fig. 3.

The same characters of reference indicate the same parts in the several figures of the drawings.

a is the lower solid lubricant, made, preferably, of the specially prepared softened wax, hereinbefore described, by which the lower or under sides of the pile-wires *c* are lubricated, and *b* is the cylinder of harder wax, by which the upper sides of the pile-wires are lubricated. The lubricating-cylinder *b* is inserted in a tubular holder *e*, carried by the ring-like end of a lever *d*, internally-projecting ribs 77 at opposite sides of the holder *e* engaging in correspondingly-shaped grooves in opposite sides of the cylinder *b*, so as to prevent the latter rotating in its holder *e*. The lower end of the cylinder *b* projects a short distance from the holder *e* and is supported on the bent end of an adjustable stop-pin 17. The cylinder is kept to

its bearing on the stop-pin 17 by a coiled spring 19, occupying the upper portion of the holder *e*, the said spring bearing at its lower end on the cylinder *b* and at its upper end against a screw-cap 16, by which the upper end of the holder *e* is closed.

The solid lubricants *a b* are so arranged and manipulated by the lubricating appliance that they are separated a short distance apart 10 while the engaging hook *f* of the ordinary pile-wire-withdrawing mechanism is drawing the eyed end of the pile-wire past the said solid lubricants and are then brought together and made to bear on the pile-wire *c*, so 15 as thereby to very efficiently lubricate the said pile-wire. When the pile-wire *c* is wholly withdrawn, the solid lubricants *a b* are again separated.

The lower end of the solid cylindrical lubricant *a* is secured in a short tubular socket 20 or holder *g*, arranged axially in a tube or case *h*, which is capable both of a rising and falling motion and also a rotary motion in a second or outer tube or case *i*, fixed by a bracket 25 *k* to the side of the loom.

Arranged at the upper end of the tube or case *h* is a plurality of pulleys *m*, over which pass cords *l*, that are attached at their inner ends to and support the holder *g* within the 30 tube or case *h*. The outer ends of the cords *l* are attached to the annular weight or ring *n*, which surrounds the tube *h* and is adapted to move up and down between said tube *h* and the casing *i*. Attached to the upper end 35 of the tube *h* and passing through an opening in the casing *i* is a suitable bracket on which is adjustably mounted a stop *o* in the form of a bent arm, the upper end of which extends over the edge of the cylindrical lubricant *a* and limits the upward movement of 40 said lubricant. It will be seen that as the cylindrical lubricant wears away it will be raised and held in contact with the stop *o* by the sinking of the annular weight *n* in the casing *i*.

The lower end of the inner tube or case *h* is attached to the head of a vertical spindle *p*, which rests on a spring-pressed lever *r*, fulcrumed at *s*, the other end of the said lever 50 having a stud *t*, which by the action of the spring *u* of the lever *r* is made to bear on a quadrant-shaped cam *v*, which turns with the lever *w* of the ordinary pile-wire-withdrawing mechanism of the loom. The cam *v* has 55 two rises, (marked, respectively, 1 2.)

The lower end of the vertical spindle *p* has on it a ratchet-wheel *y*, and carried by a spring-slide *z* on one side of the lever *r* is a spring-pressed pawl *3*. Working in conjunction with the said ratchet-wheel *y* is a spring-stop *4*. The slide *z* is attached, by means of a flexible but inelastic belt or band *5*, to a fixed bracket *6*.

The short arm of the lever *d*, by which the 65 upper lubricating-cylinder *b* is carried, is pivoted on a stationary bracket or support attached to the machine-frame and is connected

by a cord *8* to the lever *r*, so that when the lever *r* is turned on its axis in the direction proper for drawing the solid lubricant *a* away 70 from the pile-wire the motion of the said lever *r* will effect, through the cord *8* and lever *d*, the simultaneous raising of the lubricant *b*. The tubular holder *e* of the said lubricating-cylinder *b* has on it a ratchet-toothed ring or 75 collar *9*, and on one side of the lever *d* is a slotted slide *10*. The said slide *10* has on one end a spring tooth or pawl *11*, by which on the motion of the slide *10* in the direction of the arrow in Figs. 4 and 6 the ring-like collar *9* and tubular holder *e* are partially rotated, as is hereinafter described. On the other side of the lever *d* is a spring-stop *12*, (see the plan Fig. 6,) which engages with the teeth of the ratchet ring or collar *9* to prevent the back rotation of the said ring or collar *9* and tubular holder *e*. The slide *10* is operated by a supplementary lever *13*, the arms of which are slotted, the slots in the said arms working (on the motion of the lever *d*) over pins *14 15*, projecting, respectively, from the said lever *d* and slide *10*. By the engagement of the lever *13* with the pin *14* the said lever *13* is on the motion of the lever *d* rocked on its pin or axis *20*, and by the 95 engagement of the said lever *13* with the pin *15* of the slide *10* the said slide *10* is made to perform a backward and forward motion on the rocking of the lever *13*, and thereby to effect, through the spring-pawl *11* of the slide *100* *10*, a partial rotation of the ring or collar *9* and the tubular holder *e*.

The action of the lubricating appliance is as follows: When the lever *w* of the ordinary pile-wire-withdrawing mechanism of the Jacquard loom takes the full-line position represented in Fig. 1 for engaging its withdrawing-hook *f* with the eye of the next pile-wire to be withdrawn, the rise 1 of the cam *v* comes under the stud *t* of the lever *r* and effects 110 the tilting of the lever *r*, (against the action of its spring *u*,) and consequently the separation of the two solid lubricants *a b*, the tilting motion of the lever *r* being transmitted to the lever *d*, carrying the upper lubricant *b*, through the cord *8*. The motion of the lever *d* effects the partial rotation of the holder of the upper lubricant *b*, as is hereinbefore described. At the same time the downward motion of the spindle-carrying end of the lever *r* effects the pulling of the slide *z* and pawl *3* to an extent sufficient for turning the ratchet-wheel *y* through the space of about one or two teeth, in which position the said wheel is retained by the ratchet-stop *4*. On the motion of 125 the lever *w* in the direction of the arrow in Fig. 1 for withdrawing the pile-wire *c* the stud *t* descends the rise 1 of the cam *v*, and through the turning of the lever *r* under the action of its spring *u* the two solid lubricants *a b* 130 are brought together and are made to bear on the pile-wire *c* just as the eyed portion of the said wire *c* has passed the said solid lubricants. On the lever *w* completing its back

motion, as indicated in dotted lines, the second rise 2 of the cam *v* comes under the stud *t* and again effects the separation of the two lubricants *a b* and also the partial rotation 5 through a small angle of the said lubricants *a b*. By the intermittent partial rotation of the solid cylindrical lubricants *a b* the grooving of the acting ends of the same which would result from continually drawing the 10 pile-wires across the said ends in the same line is prevented.

The automatic adjustment of the solid cylindrical lubricant *a* to compensate for wear or consumption of the lubricant is effected 15 by the annular weight *n*.

Although I prefer to employ both lubricants *a* and *b*, yet I wish it to be understood that the solid lubricant *a* only may be employed.

20 It will be understood by those conversant with Jacquard and like looms that as each of the pile-wires is in its turn brought opposite the lubricating appliance, hereinbefore described, all the said wires are successively 25 and automatically lubricated on their withdrawal from the carpet.

By lubricating the pile-wires with solid lubricants in the ways hereinbefore described not only is the soiling of the carpet with liquid oil prevented, but the slay and pile-wires 30 are preserved clean and other minor advantages result therefrom.

Having now described my invention, what I claim as new, and desire to secure by Letters Patent, is—

35 1. In a device for lubricating the pile-wires of looms, the combination with an engaging hook for withdrawing pile-wires, and operating means therefor, of a lever oscillated by said operating means, a lubricating-cylinder revolvably mounted on said lever, and means operated by the oscillation of said lever for revolving said lubricating-cylinder.

40 2. In a device for lubricating the pile-wires of looms, the combination with an engaging hook for withdrawing pile-wires, and operating means therefor, of a lever oscillated by said operating means, a lubricating-cylinder, a holder for said lubricating-cylinder, a ratchet-wheel on said holder, a slide on said lever, a pawl on said slide in engagement with said ratchet-wheel, a stationary member, and a connection between said stationary member and said slide, whereby said slide is 45 actuated by the oscillation of said lever to revolve said holder.

45 3. In a device for lubricating the pile-wires of looms, the combination with an engaging hook for withdrawing pile-wires, and operating means therefor; of a lever oscillated by said operating means, a lubricating-cylinder on said lever, a second lever oscillated by said first-mentioned lever, and a lubricating-cylinder on said second lever.

50 4. In a device for lubricating the pile-wires of looms, the combination with an engaging hook for withdrawing pile-wires, and operat-

ing means therefor, of a lever oscillated by said operating means, a lubricating-cylinder on said lever, means for revolving said cylinder, a second lever oscillated by said first-mentioned lever, a lubricating-cylinder on said second lever, and means for revolving said last-mentioned lubricating-cylinder.

55 5. In a device for lubricating the pile-wires of looms, the combination with an engaging hook, and operating means therefor, of a lever oscillated by said operating means, a lubricating-cylinder on said lever, a second lever, a lubricating-cylinder on said second lever, and a flexible connection between said levers, whereby, when said first-mentioned lever is oscillated, its motion is communicated to said second lever and said levers are thereby caused to simultaneously approach and recede from one another.

60 6. In a device for lubricating the pile-wires of looms, the combination with the engaging hook, and operating means therefor, of a lever oscillated by said operating means, a lubricating-cylinder on said lever, means for revolving said lubricating-cylinder, a second lever, a lubricating-cylinder on said second lever, means for revolving said last-mentioned lubricating-cylinder, and a flexible connection 65 between said levers, whereby, when said first-mentioned lever is oscillated, its motion is communicated to said second lever, and said levers are thereby caused to simultaneously approach and recede from one another.

70 7. In a device for lubricating the pile-wires of looms, the combination with an engaging hook for withdrawing pile-wires, of an oscillating arm for operating said engaging hook, a cam oscillating with said arm, a lever bearing at one end upon said cam, a lubricating-cylinder upon said lever, a second lever, means for oscillating said second lever, and a lubricating cylinder upon said second lever.

75 8. In a device for lubricating the pile-wires of looms, the combination with an engaging hook for withdrawing pile-wires, of an oscillating arm for operating said engaging hook, a cam oscillating with said arm, a lever bearing at one end upon said cam, a lubricating-cylinder, a holder for said lubricating-cylinder, a ratchet-wheel upon said holder, a slide upon said lever, a pawl upon said slide in engagement with said ratchet-wheel, a spring for returning said slide to operative position, a stationary member, a connection between said stationary member and said slide, whereby said slide is actuated by the movement of said lever, a stationary support, a second lever pivoted upon said support, a pin or projection on said second lever, a second lubricating-cylinder, a support for said second lubricating-cylinder, a ratchet-wheel on said last-mentioned support, a slide on said second lever, a pin or projection on said slide, a pawl on said slide in engagement with said last-mentioned ratchet-wheel, an angle-piece or 80 supplementary lever pivoted upon said stationary support, said angle-piece having a

85 9. In a device for lubricating the pile-wires of looms, the combination with an engaging hook for withdrawing pile-wires, of an oscillating arm for operating said engaging hook, a cam oscillating with said arm, a lever bearing at one end upon said cam, a lubricating-cylinder, a holder for said lubricating-cylinder, a ratchet-wheel upon said holder, a slide upon said lever, a pawl upon said slide in engagement with said ratchet-wheel, an angle-piece or supplementary lever pivoted upon said stationary support, said angle-piece having a

slot in each of its ends, the slot in one end of
said angle-piece engaging with the pin or pro-
jection on said second lever, and the slot in
the other end of said angle-piece engaging
5 with the pin or projection on the slide which
is mounted on said second lever.

In testimony whereof I have hereunto set

my hand in presence of two subscribing wit-
nesses.

CHARLES BAULK.
